UNITED STATES PATENT OFFICE

HERMAN P. WEIMAN, OF DAVENPORT, IOWA, ASSIGNEE TO HENRY GOSCH, OF
DAVENPORT, IOWA

WASHING MACHINE

Application filed December 31, 1930. Serial No. 505,895.

This invention relates to washing machines and particularly to that form of washing machine in which an oscillatable tub is provided and means are also provided whereby the 5 tub may be oscillated and the clothes shifted from side to side within the tub.

The general object of the present invention is to provide a device of this character which is very simple, which may be cheaply 10 made, which has been found very effective in practice and in which the clothes are caused, as they are thrown outward by centrifugal force, to be swung through the water or held while the water in the tub washes 15 them and when the clothes move inward to the center of the tub upon a momentary cessation of the rotation, the clothes will be again engaged and whirled about upon an oscillation of the tub.

20 A further object is to provide a construction of this character in which three different projections or projecting members in the tub act to engage the clothes upon an oscillation of the tub, thus causing the clothes to be 25 washed at three different points within the tub.

Another object is to provide a machine of this character which has no dasher post in the center, thus doing away with expensive 30 water-tight bearings in the bottom of the tub.

Other objects have to do with means whereby the machine is oscillated.

My invention is illustrated in the accompanying drawings, wherein:—

Figure 1 is a vertical sectional view through a washing machine constructed in accordance with my invention;

Figure 2 is a section on the line 2—2 of Figure 1;

Figure 3 is a section on the line 3—3 of Figure 1;

Figure 4 is a top plan view of the machine on a reduced scale.

45 Referring to these drawings, 10 designates a tub which may be made of sheet metal, sheet aluminum, or of any other suitable material. This tub has a flat central portion at its bottom and an upwardly inclined portion 11. The flat bottom of the tub is engaged by

a cast iron base 12 having a hub portion 13. From this cast iron base extend upward the arms 14 which are offset at their upper ends and have riveted to them the angular brass pieces 15. The tub is soldered to these brass 55 pieces 15. The tub at its upper end is formed with the inwardly extending splash ring 16. Passing through the hub portion 13 and attached to this hub portion in any suitable manner is a shaft 17. Disposed within the 60 tub are four wings constituting a dasher designated 18 which is held to the bottom of the tub and to the shaft by means of the bolt 19 or in any other suitable manner. Normally closing the opening defined by the 65 splash ring 16 is a lid 20 to which is riveted an aluminum ring carrying depending pins 21.

Extending upward from the inclined portion 11 of the tub are a plurality of vertical 70 members 22 which are preferably made of copper and soldered to the tub or otherwise attached thereto. These extend upward to the splash ring and are held to the splash ring by aluminum knobs 23 bolted on the 75 splash ring.

The shaft 17 and the tub are oscillated by mechanism as follows. The tub is housed within an exterior housing 24 and extending downward through this housing exteriorly 80 of the tub is a driving shaft 25 which may be driven in any suitable manner and which is mounted in a supporting bearing 26 and a housing 27. I have illustrated the lower end of this driving shaft within the housing 27 85 as being provided with the worm wheel 28 engaged by a worm 29, this worm shaft being the driving shaft and connected to any suitable source of power. The shaft 25 carries adjacent the housing 27 a crank 30. 90 From this crank extends a connecting rod 31. This connecting rod is slidably engaged with a swiveled pin or head 32 mounted upon a segment gear 33 pivotally mounted upon the frame of the machine at 34. This segment gear engages with a gear wheel 35 which is mounted upon the shaft 17 in any suitable manner. Springs 36 are attached at their inner ends to the bottom of the tub 95 and at their outer ends to hooks 37 on a sup- 100

porting frame member 38, these springs tending to hold the tub against oscillation in either direction and to return the tub to a normal position.

5 Disposed on each side of the swiveled pin 32 and surrounding the connecting rod are the springs 39, these being coiled compression springs which bear at their inner ends against the swiveled pin 32 and at their outer ends against stops 40.

10 It will be obvious now that as the shaft 25 is rotated, the connecting rod 31 will be oscillated which will oscillate the segment gear 33 and cause the oscillation of the tub in opposite directions. The gear wheel 35 is loose upon the shaft 17 and for the purpose of connecting the shaft operatively to this gear to cause an oscillation of the shaft, I provide the sliding clutch 41 mounted upon 15 the shaft and having rotative engagement therewith of any desired character. The upper face of this clutch is toothed, notched or otherwise formed to engage with the under face of the gear wheel 35. The clutch is 20 shifted into or out of engagement with the gear wheel 35 by means of a bell crank lever 42 pivoted upon a bracket 43. The depending arm of this bell crank lever is pivoted to a connecting rod 44 which in turn is 25 connected to a crank arm 45 mounted upon the lower end of a vertical shaft 46 which extends up through the outer housing 24 and is provided with a handle at its upper end. Thus the clutch may be shifted into or out of 30 engagement with the gear wheel. The shaft 17 may be supported in any desired manner but I have shown the shaft as being supported on a ball step bearing designated generally 47 resting upon a transverse cross bar 48 35 of the frame. The shaft 25 may constitute also a wringer shaft extending upward through the housing and operatively connected to a wringer in a manner not shown.

40 The tub is provided with the discharge spout 49 whereby the water may be run off from the tub.

45 While I have heretofore described the construction used where the tub is of cast iron, yet in case it is a cast aluminum tub, the wings of the dasher 18 are cast with the tub and the lower ends of the copper pipe 21 are held in place by aluminum knobs like the knobs 23.

50 The brass pieces 15 will not be used under these circumstances. The operation of the tub will be obvious from what has gone before. The intermittent half turns which the tub makes under the action of the driving mechanism, causes the water to move outward by centrifugal force from the center to the sides of the tub carrying with it the clothes. At the sides of the tub, the copper pipes 21 engage the clothes and swing them 55 through the water. Upon the momentary stoppage between the movement of the tub

in one direction and its reversal, the clothes will move toward the center of the tub and will be engaged by the pins 21 and by the dasher. Thus the clothes are washed as it were at three different places while the clothes make one turn in the tub. It will be seen no dasher post is necessary in this mechanism and that the interior of the tub is entirely free from any complicated mechanism.

70 The purpose of the springs 36 is to pull the tub straight with the spout 49 to the front when the tub is out of gear and to make the tub come back easily and to stop the swing of the tub which it would ordinarily have through its own weight.

75 I claim:—

1. A washing machine including a tub, driving means for oscillating the tub alternately in opposite directions, the tub having a bottom flat at its central portion and then extending upward and outward to the side of the tub, the side of the tub extending vertically upward, the top of the tub having an inwardly extending splash ring, upstanding wings forming a dasher and mounted upon the central portion of the tub, members extending downward from the splash ring to the inclined portion of the bottom of the tub, and a cover for the tub having downwardly extending pins.

80 2. A washing machine including a tub, the tub having a bottom flat at its central portion and then extending upward and outward to the side of the tub, the side of the tub extending vertically upward and having at its top an inwardly extending splash ring, upstanding radially disposed wings mounted upon the central portion of the tub and constituting a dasher, members attached at their upper ends to the splash ring and extending down and attached to the downwardly and centrally inclined portion of the bottom of the tub, a removable cover for the tub having downwardly extending clothes engaging pins disposed over the central portion of the tub, and means for alternately oscillating the tub in opposite directions.

85 100 105 110 115 In testimony whereof I hereunto affix my signature.

HERMAN P. WEIMAN.
